UNITED STATES PATENT OFFICE.

CHARLES A. OLSON AND CLAUDE H. TOOMBS, OF GENEVA, ILLINOIS.

WRENCH.

1,243,860.

Specification of Letters Patent.

Patented Oct. 23, 1917.

Application filed March 10, 1915. Serial No. 13,451.

To all whom it may concern:

Be it known that we, CHARLES A. OLSON and CLAUDE H. TOOMBS, both citizens of the United States, and both residing at Geneva, 5 in the county of Kane and State of Illinois, have invented new and useful Improvements in Wrenches, of which the following is a full, clear, concise, and exact description; reference being had to the accompanying drawing, forming a part of this specification.

Our invention relates to wrenches and particularly to the type known as socket wrenches.

It is one of the objects of our invention to 15 provide a simple, compact, efficient wrench, easily and quickly adjustable to take nuts of various sizes and adaptable to nuts of various shapes and styles.

It is another object of our invention to 20 provide a wrench of the sort described which, in its construction, combines great durability and strength with extreme economy and ease of manufacture.

Additional objects and advantages of our 25 invention will be apparent from the following description taken in connection with the appended claims.

We have described in the following specification and illustrated in the accompanying 30 drawings an embodiment of our invention, it being understood that changes may be made in the form, construction and arrangement of the parts without departing from the spirit of the invention or exceeding the scope 35 of the appended claims, the form of the invention herein disclosed being merely a preferred embodiment thereof.

In the drawings:

Figure 1 is a view in side elevation of a 40 wrench constructed in accordance with our invention, showing the interior parts in dotted lines, with jaw members withdrawn;

Fig. 2 is a cross-sectional view of the same showing the jaw members extended;

Fig. 3 is a view in end elevation from the right of Fig. 2;

Fig. 4 is a detail showing in perspective one of the duplicate jaw members;

Fig. 5 is a view partially in cross section 50 and partially in elevation showing a modification of the wrench illustrated in Figs. 1 and 2; and

Figs. 6 and 7 are cross-sectional views taken on the lines 6-6 and 7-7 respectively, 55 of Fig. 5, looking in the direction of the arrows.

Referring to the drawings, the body portion of the wrench is composed of an open ended cylindrical sleeve or tube 10 which is made from ordinary stock tubing. Fitting in one end of this tube 10 are a pair of jaw members 11 which are identical and which are longitudinally adjustable in the tube as will more fully hereinafter appear. The opposing inner faces 12 of these jaw 60 members are flat and the outer surfaces 13 are formed to correspond with the adjacent inner surface of the sleeve or tube 10 in any position as more fully hereinafter appears. The inner flat surface of each jaw member 65 is formed with a V-shaped cut 14 at the end so that the two corresponding cuts form jaws for grasping a nut. At their edges, as indicated at 15, the jaws are cut flat in order that they can take hold of a flat strip or the 70 wings of certain types of wing nuts when desired. And complementary longitudinal grooves 16 extending inwardly from the shoulder formed by the jaws 14 provide a hole by means of which the wrench can grasp 75 the end of a bolt or the like. This hole also provides clearance for the end of a bolt in case the wrench is used with a nut beyond which the bolt projects. For more effectively grasping a rod or the like the grooves 80 85 16 forming this hole are provided with longitudinal teeth 16^a. The jaws are provided with a hinged relation by means of a pin 17 which fits in a hole formed by complementary transverse grooves 18 cut in the flat 90 surfaces of the jaw members 11 near the inner ends thereof. This pin also serves to adjustably connect the jaw members to the tube 10 as each end of the pin 17 passes through a slot 19 cut in the wall of the tube, 95 and is headed over as shown at 20 so as to secure the parts in place. From their outer ends the jaw members 11 are tapered inwardly for a distance corresponding to the length of the slot 19, as appears in Fig. 1, or 100 in other words, corresponding to the extent of their longitudinal displacement. From this point, they are tapered outwardly to their inner ends at which points they are, together, of a diameter to fit the tube. The 105 transverse curve of the outer surfaces of these members at all points corresponds to the curve of the inner surface of the tube. Due to this construction a portion of each of the jaw members is always in snug contact with the tube regardless of the longitudinal position of the members. The jaw 110

members may be extended beyond the end of the tube or withdrawn into the tube by moving the pin 17 back and forth in the slots 19. This operation causes the jaws to open or close to provide an opening of the desired size, for as the jaws are extended beyond the tube, a coiled spring 21, each end of which sits in a suitable recess 22 in the flat face of the jaw member, forces the jaws apart, the extent of such opening being limited by the engagement of the jaw members with the tube. Due to the construction described the farther the jaws are extended beyond the end of the tube the wider they will open. The force of the spring is sufficient to provide enough friction between the jaw members and the tube to hold the jaws in any position to which they may be moved. As will be apparent, upon withdrawal of the jaws by a movement of the pin in the opposite direction, the engagement of the tube with the tapered surfaces 13 causes the jaws to close. If desired, instead of utilizing the pin 17 as a means of opening and closing the jaws, the wrench may be given a quick jerk as by the sudden downward movement of the arm. This will cause the jaw members to be extended to the full open position. The jaws may then be placed over the nut and pressure on the wrench will cause the jaws to close to the desired extent.

The wrench is operated by a handle 23 which may be of the form and shape desired, the form shown being an ordinary steel rod. This handle is inserted through diametrically opposed holes 24 cut in the tube 10 near the end thereof. For convenience and in order that the handle may be placed in the proper relative position there are two sets of these holes as shown in Fig. 5.

In Fig. 5 is illustrated a modification of the wrench just described. This form also has a cylindrical tube 10 and a pair of identical jaw members 11 which have flat inner opposing faces 12 and tapered outer surfaces 13, the curve of which, at all points, corresponds with the adjacent inner surface of the tube as before described. The jaw forming ends of the members 11 are formed just as the similar parts above described. Near the inner end of the jaw members are cut complementary channels forming, together as shown in Fig. 5, a slot 25 for the reception of a pin 26 which passes through the tube 10 at diametrically opposed points, the ends being riveted or otherwise secured in place. The jaw members 11 have recesses 22 for receiving a coiled spring 21 as before described for causing the jaws to open as the members 11 are withdrawn from the tube and these members are held together in proper relative position by a pin 27 fitting in suitable grooves near their inner ends, thus giving the members a hinged relation.

As will be apparent, in this form of

wrench the pin 26 is stationary and the jaw members ride on it by means of the slot 25. The jaw members are extended to open the jaws by giving the wrench a sudden jerk as by the quick downward movement of the arm. This will ordinarily open the jaws to their full extent and they are closed by pressure on the wrench.

It is thought that the operation of the wrench will be clear from the foregoing description. To recapitulate, the adjustment of the jaws to provide the opening desired is attained by movement of pin 17 in the slots 19 or by the sudden jerk of the wrench and subsequent pressure on the wrench against the article being operated on. In either case the jaws are forced open during extension of members 11 by the spring 21 and are closed on withdrawal by the contact of these members with the tube. The jaws having been adjusted to provide suitable engagement with the nut or other article, the wrench is turned by means of the handle and, as will be seen, the turning torque of the tube is transmitted to the jaw members through the medium of the pin 17 or pin 26. Through these pins, also, the torsional strain of operation is distributed evenly, thus bringing such torsional strain in balance with respect to the axis of the sleeve and the wrench as a whole. Pin 17 or pin 26 passing through the sides of the tube 10 serves also to hold the jaw members against relative rotation within the tube.

A wrench embodying our invention has numerous advantages in construction and use. Every part may be made from standard stock. The tube may be cut from stock tubing of suitable size; the pin may be formed from an ordinary rod and the jaw members may be fashioned from commercial half round stock. And as the jaw members are counterparts only one set of forming tools is required.

A cylindrical tube of this sort, in addition to being extremely economical to produce, is likewise very efficient and durable. For, as it is circular in cross section throughout it provides throughout a section of maximum strength. Likewise, the form of the jaw members makes for combined economy and efficiency. They are of a cross section to give maximum strength, they provide maximum contact with the tube, which tends to prevent side motion or rocking during operation of the wrench, and they fit the inside of the tube so that the jaws, when opened, are held in proper relative alignment.

This wrench is extremely simple to operate and its adjustments may be made almost instantly as there are no screws or other complicated parts to manipulate, all that is necessary being the movement of the jaw members in the tube by means of opera-

tion of the pin 17 in its slot or by a quick jerk of the wrench, as the case may be. It will take hexagon, square, wing and cock nuts, and nuts that are worn, flats, studs 5 and ends of bolts, all equally well. It cannot slip as the jaws have rigid bearing on four sides and the harder one pulls the harder the jaws grasp the nut.

Another advantageous feature is that the 10 wrench holds the nut after removal, or the nut may be placed in the jaws and thus applied to its bolt in locations inaccessible to the hands.

When the jaws are withdrawn into the 15 cylindrical tube and the handle removed the wrench presents a compact article with no protruding or irregularly shaped parts so that it can be easily carried and packed.

The various advantages and benefits derived from this wrench as above noted are 20 taken merely as examples and many more, which it is considered inexpedient to set forth here, will be apparent to the wrench user.

Having thus described our invention what 25 we claim as new and desire to secure by Letters Patent is:—

1. A socket wrench comprising a tube having a cylindrical bore, a pair of jaw 30 members slidably fitting in said tube, said jaw members being substantially semi-cir-

cular in cross section, said jaws having opposing grooves extending completely across the flat faces of said jaw members, and a pin lying in said grooves and forming a 35 bearing pin for said jaw members, said tube having diametrically opposed openings in its sides into which the ends of said pin extend for transmitting torsion from said tube to said jaws, said jaw members having opposed recesses therein forming a socket substantially co-axial with said tube. 40

2. A socket wrench comprising a tube having a cylindrical bore, a pair of jaw 45 members slidably fitting in said tube, said jaw members being substantially semi-circular in cross section and a pin forming a pivot for said members, said tube having diametrically opposed slots in its sides into which the ends of said pivot pin extend for 50 transmitting torsion from said tube to said jaws, said jaw members having opposed recesses therein forming a socket substantially co-axial with said tube.

In witness whereof, we have hereunto 55 subscribed in the presence of two witnesses.

CHARLES A. OLSON.
CLAUDE H. TOOMBS.
